UNITED STATES PATENT OFFICE.

LAWRENCE RICHARDSON, OF LOUISVILLE, KENTUCKY.

SIDE BEARING FOR RAILWAY CARS.

Application filed August 6, 1923. Serial No. 655,831.

This invention relates to side bearings for railway cars.

As the capacity of bolsters has increased, the side bearing loads have become increasingly important. With the same design assumptions, it has been found that the percentage of bolsters developing side bearing trouble is greater with higher capacity bolsters. Investigation into the reason for this trouble reveals the fact that the lateral blows play a large part. This is especially true when the side bearings are located at a plane higher than the center plates.

Accordingly, one object of my present invention is to overcome the excessive lateral blows on side bearings.

Another object is to provide a simple, durable and efficient side bearing whereby the lateral blows are taken primarily at the center plates, thereby relieving the side bearings.

These and other objects are accomplished by means of the arrangement disclosed on the accompanying sheet of drawings, in which—

Figure 1 is a fragmentary vertical sectional view of a railway car constructed in accordance with my invention, and

Figure 2 is a plan view of the disclosure of Figure 1 taken on line 2^x—2^x.

It will be noted that the invention is illustrated in connection with a box car having a body 10 and body bolster 11 under which the center sill structure 12 is located, said center sill at each end carrying an upper center plate 13 which cooperates with a lower center plate 14 carried by a truck bolster 15.

In view of the fact that the center plates are designed for severe lateral stresses, the side bearings should be relieved as much as possible from such lateral stresses, especially in high capacity cars where the lateral stresses are excessive. In cases such as the one illustrated, wherein the center plate 14 is on a plane lower than the side bearings, it will be appreciated that a relatively heavy lateral blow would be delivered to the lower side bearings by the upper side bearing of the usual type if the tracks were irregular, causing a swaying back and forth of the car body. Or again, in going around a sharp curve to the right with the left hand rail banked, it will be appreciated that the lower bearing on the left hand side will be raised and the upper bearing on the left hand side will have a tendency to lower in view of the

fact that the car body will have a tendency to continue in the same direction in which it was moving before the curve was reached. The result would be that a relatively heavy lateral blow would be delivered to the lower left hand bearing. A similar blow would be delivered to the lower right hand bearing if the truck curved to the left and if the right hand rail were banked. Such side bearing blows, as mentioned above, are excessive, especially in the present day high capacity cars using heavy bolsters, and it is primarily the object of this invention to overcome such heavy lateral blows to the lower side bearing members and to permit the center plate, which is designed for excessive lateral blows, to assume the latter.

To this end the upper side bearings 16 carried by the body bolster have their lower surfaces inclined, extending downwardly and outwardly. In a similar manner the lower side bearings 17 carried by the truck bolster structure have their upper cooperating surfaces inclined downwardly and outwardly. As a result thereof when the car body sways from one side to the other and the side bearings 16 and 17 on one side pass into engagement with each other, instead of there being a heavy lateral load delivered to the lower side bearing 17, there is a relative lateral frictional sliding movement of the upper and lower side bearings, such lateral sliding movement continuing until the lateral movement is checked by the center plates.

From the disclosure in Figure 2, it will be observed that the bearing portions 16 and 17 are arcuate, having a curve struck from the pivot center of the center bearing, thus maintaining the same spaced relationship between the upper and lower bearing members for all positions of the bolsters 11 and 15 relative to each other, irrespective of the angular displacement caused when the car travels around a curve.

While in the illustration here shown the side bearings are located at a higher plane than the center plates, it will be appreciated that even with the side bearings on a level with the center plates, it is possible to develop lateral blows on the side bearing by an outward movement of the car body on the side bearings and center plate surfaces in the constructions which have been used heretofore. However, by inclining the side bearings outwardly, as shown, these excess-

sive lateral blows are obviated. The inclined side bearing surfaces can take only a load imposed at right angles to the contact surfaces plus a frictional load parallel to the surfaces. This frictional load is equal to the normal vertical load multiplied by the coefficient of friction. Any lateral blow in excess of this combination is naturally transferred to the center plate, but the center 10 plate is usually designed for severe lateral stresses and therefore can assume the one in question with very little additional metal, if any. The relief of the lateral blow naturally is proportional to the angle of inclination.

15 It is my intention to cover all modifications of the invention falling within the spirit and scope of the following claims.

I claim:

1. In a railway car, the combination of a body bolster, a truck bolster and side bearing parts immovably fixed on each of said bolsters, said parts having cooperating surfaces inclined at a predetermined angle, said angle being calculated to reduce lateral friction between said bearing parts a predetermined amount which amount is sufficient to eliminate the absorption of a predetermined amount of the lateral force, by the side bearing parts.
- 25 2. In a railway car, the combination of a body bolster, a truck bolster, center plates associated therewith, and side bearing parts

immovably fixed on each of said bolsters and having cooperating surfaces inclined at a predetermined angle, said angle being calculated to reduce lateral friction between said bearing parts a predetermined amount which amount is sufficient to eliminate the absorption of a predetermined amount of the lateral force, by the side bearing parts.

3. In a railway car, immovably fixed bearing parts having cooperating surfaces inclined at a predetermined angle, said angle being calculated to reduce lateral friction between said bearing parts a predetermined amount which amount is sufficient to eliminate the absorption of a predetermined amount of the lateral force, by the side bearing parts.

4. In a railway car, immovably fixed side bearings at each side of the car having cooperating surfaces which extend downwardly and outwardly at a predetermined angle with respect to the center of the car, said angle being calculated to reduce lateral friction between said bearing parts to predetermined amount, which amount is sufficient to eliminate the absorption of the predetermined amount, whereby substantially all the lateral force is taken on the center bearing.

Signed at Chicago, Illinois, this 3rd day of August 1923.

LAWRENCE RICHARDSON.
